FUEL-CHARGING DEVICE

Application filed October 29, 1924. Serial No. 746,659.

This invention relates to improvements in a fuel charging device for an internal combustion engine.

It is among the objects of the present invention to automatically vary the quantity of liquid fuel delivered to the carburetor of an internal combustion engine, in accordance with the engine suction.

Another object of the present invention is to provide a liquid fuel metering device of simple structure and design including substantially frictionless, movable elements and which is adapted to deliver a fuel flow of sufficient capacity at low engine suctions and a flow of greater capacity when the suction of the engine reaches a greater value.

These objects are attained by means of a metering device including a stationary metering element having an orifice of maximum fuel flow capacity and a floating metering element provided with an orifice of comparative lesser fuel flow capacity than the stationary element, this latter floating element being adapted normally to obstruct the stationary element and thus control the quantity of fuel being delivered to the engine at low suction.

However, as soon as the suction effective on said floating element becomes sufficient, it will be moved from normal position and permit the functioning of the stationary element thus delivering a greater quantity of fuel to the engine under this increased suction condition.

Further objects and advantages of the present invention will be apparent from the following description reference being had to the accompanying drawings, wherein a preferred embodiment of one form of the present invention is clearly shown.

40 In the drawings:

Fig. 1 is a sectional view showing the liquid fuel charging device combined with the intake port of one engine cylinder;

Fig. 2 is a detail sectional view of the metering means and conduit of the charging device; and

Fig. 3 is a transverse section taken through line 3—3 of Fig. 2.

Referring to the drawings, the numeral 20 designates the liquid fuel supply device

which comprises the casting 21 including the top plate 22 having a hollow, depending portion 23, termed the conduit hereinafter. The edge of the bowl 24, which forms the fuel reservoir, fits into a circular groove formed in the top plate 22, and is rigidly held in this position by the stud 25 which passes through a central opening in the bottom of the bowl and screws into the end of the conduit 23, forming a plug for this end of the conduit. A gasket 26 is interposed between the end of the conduit 23 and the surface of the bowl to prevent leakage at this point.

55 The liquid fuel line connection is designated by the numeral 27 and is provided with the well known float-operated control valve not shown in the drawings. The float is designated by the dotted lines.

60 The top plate 22 has a central projecting portion in which is formed the main liquid fuel distributing canal 29 and its two vertical passages 30 and 31.

65 The diameter of the interior passage of the conduit varies. The portion 32 which communicates with the canal 29 is of lesser diameter than the portion 33 which in turn communicates with the interior of the reservoir by means of the cross passages 34 and 35. Within the portion 33, between the reduced portion 32 and the cross passages 34 and 35 there are provided screw threads which support plug 36 having the metering orifice 37. The metering orifice 37 is of a predetermined size, sufficient to deliver enough fuel for all engine demands. On each side of the element 36 and concentric with the orifice 37 there is provided a counterbore 38.

70 Inside the passage 33 between the stationary metering element 36 and the passage 32 there is provided a floating valve or metering element 39. This element is constructed of any suitable material, being of lesser transverse diameter than the passage 33 in order to eliminate frictional contact therewith and permit the passage of fuel through the space between the passage wall and the metering element. It is hollowed out and slotted at its one end to provide lightness and rounded off at its other end to permit this end normally to fit into and rest on the peripheral

edge of the counterbored portion of the stationary metering element 36 thereby substantially preventing the passage of any fuel, but compelling it to flow through the longitudinal orifice 40 formed therein, said orifice being of lesser capacity than that of the stationary element.

The liquid fuel supply device 20 is secured to the distributing head 45 in any suitable manner, a gasket 46 being provided between them to prevent leakage at the joint. A chamber 47, open to atmosphere, is formed in the head 45 said chamber having a series of passages 48 leading therefrom, each of said 10 passages having a pipe 49 communicating therewith. In the present drawings each of the vertical passages 30 and 31 are shown in communication with one of the passages 48, the passage 30 by means of the passage 20 50 and 31 by means of passage 51.

The vaporizing or mixing device of the fuel charger is designated by the numeral 55, and comprises a body 56 suitably secured to the intake port 57 of the engine cylinder 58.

25 A throttle valve 59 is provided in the mixing device adjacent the engine port 57. Within the body 56 there is positioned a Venturi tube 60. At the restricted portion of this tube, and formed about its outer periphery 30 is a circumferential groove 61. A plurality of passages 62 provide communication between this groove and the interior of the tube. A nozzle 63 is provided in the restricted neck portion of the venturi, one end 35 of the nozzle extending into the groove 61 while the other end extends into the interior of the Venturi tube to approximately its center. An air controlling valve 65 of any suitable type is provided on the body 56 in 40 connection with the passage 64 said valve being adapted to control the secondary air feed through the passage 64 in accordance with the suction of the engine.

The groove 61 of the venturi is in communication with the pipe 49 of the distributing head 45 by means of the fuel connection which comprises a barrel portion 68 held onto the mixing device by means of a stud 69. The pipe 49 fits into a projection 70 50 formed on the portion 68 and communicates with the interior of this portion 68. The stud 69 is provided with passages 71 and 72 forming communicating channels between the interior of the portion 68 and the groove 55 61.

In operation the device functions as follows: Suction from the engine cylinder 58 will cause a secondary air flow through a controlling valve 65 connected with the passage 64, thence through the venturi, past the throttle 59 into the intake port 57. The primary air enters the chamber 47, flows through the passage 48 where it is mixed with fuel to form a primary mixture, which 60 flows through pipe 49 and the interior of

the barrel portion 68. Then the primary mixture flows through passages 71 and 72 enters the groove 61 and passes through passages 62 into the Venturi tube 60 where it mingles with the secondary air.

The depression in the passage 48 will cause liquid fuel to flow from the reservoir 24 through passages 34 and 35 into the passage 33 below the stationary metering element 36. Now, when the suction of the engine is insufficient to cause the floating valve 39 to be lifted off its seat on the plug 36, the plug 36 70 will not function as a metering device but as an ordinary fuel passage to the valve element 39 which will act as the metering means under these conditions.

After being metered by the valve element 39 the fuel will flow through passages 33 and 32, enter the distributing canal 29 and pass into vertical passages 30-50 and 31-51. 75 The air flowing past the mouth of the passage 50 will pick up the fuel in said passage and carry it through pipe 49 into chamber of barrel 68 through passages 71 and 72 into the groove 61. The fuel laden air will pass through passages 62 into the venturi and unite with the secondary air flow from passage 64. The unvaporized particles of the fuel from passage 72 will tend to fill the groove 61 and when the level of the liquid fuel in the groove attains a height equal to the height of the nozzle 63 the secondary air flow from the passage 64 will carry off any excess fuel flowing out of this nozzle during the operation of the engine at comparatively 80 low suctions.

When the engine suction increases sufficiently to lift valve 39 from its seat on the metering element 36, functioning of the element 39 to meter fuel will cease. Under this condition the quantity of the liquid fuel delivered to the engine will be controlled by the metering element 36 which as has been mentioned heretofore is of greater flow capacity than the element 39.

105 While the form of embodiment of the invention as herein disclosed, constitutes a preferred form, it is to be understood that other forms might be adopted, all coming within the scope of the claims which follow.

110 What is claimed is as follows:

1. A charge forming device for supplying a mixture of air and liquid fuel to an internal combustion engine comprising: a mixture forming passage having an air inlet and a fuel inlet thereto, a fuel duct for leading liquid fuel to said fuel inlet, a main restricting orifice in said fuel duct for limiting the maximum flow of fuel therethrough, and a gravity actuated valve adapted to cooperate with said orifice, said valve having an aperture therein for limiting the flow of fuel through said fuel duct when said gravity valve is seated, and being of such predetermined weight that it is lifted from its seat by 115 120 125 130

the liquid fuel stream at higher engine suction.

2. A charge forming device for supplying a mixture of air and liquid fuel to an internal combustion engine comprising: a mixture forming passage having an air inlet and a fuel inlet thereto, a fuel duct for leading liquid fuel to said fuel inlet, a main restricting orifice in said duct for limiting the maximum flow of fuel therethrough, and a valve in said duct entirely immersed in the liquid fuel therein adapted to cooperate with said orifice at low engine suction, said valve having an aperture therein for limiting the flow of fuel through said fuel duct when said valve is seated, and being held upon its seat by such small force that it is lifted from its seat by the liquid fuel stream at higher engine suction.
3. A charge forming device for an internal combustion engine comprising a mixture passage, fuel and air inlets therefor, a fuel reservoir, a fuel duct connecting the fuel inlet with said reservoir, a valve in said duct regulating the flow of fuel therethrough, said valve having an aperture therein for limiting the flow of fuel through said duct when the valve is in closed position and adapted to be opened by the action of the fuel flowing through said fuel duct on increase in engine suction effective on the fuel inlet.

In testimony whereof I hereto affix my signature.

FRED E. ASELTINE.
